UNITED STATES PATENT OFFICE

125,934

DESIGN FOR A POOL TABLE OR ANALOGOUS ARTICLE

Anthony Paul Jalwan, Clarksburg, W. Va.

Application December 23, 1940, Serial No. 97,576

Term of patent 14 years

To all whom it may concern:

Be it known that I, Anthony Paul Jalwan, a citizen of the United States, residing at Clarksburg, in the county of Harrison and State of West Virginia, have invented a new, original, and ornamental Design for a Pool Table or Analogous Article, of which the following is a specification, reference being had to the accompanying drawings, forming part thereof.

I claim:

The ornamental design for a pool table or analogous article, as shown.

ANTHONY PAUL JALWAN.
